W. H. REICHARD

CONTINUOUS INDUCTIVE TRAIN CONTROL SYSTEM

Filed May 24, 1926

UNITED STATES PATENT OFFICE.

WADE H. REICHARD, OF ROCHESTER, NEW YORK, ASSIGNOR TO GENERAL RAILWAY SIGNAL COMPANY, OF ROCHESTER, NEW YORK.

CONTINUOUS INDUCTIVE TRAIN-CONTROL SYSTEM.

Application filed May 24, 1926. Serial No. 111,289.

This invention relates to automatic train control systems of the continuous inductive type.

In train control systems of the two position or two condition continuous inductive type, the train is permitted to proceed in response to train control current flowing down one rail of the trackway through the axles of the train and back through the other rail, that is, in response to current flowing in the usual track circuit. For well known reasons if the train is permitted to proceed in response to current flowing in the usual track circuit this same current cannot be used for controlling the track relay, because it is necessary to cut off the train control track circuit current in a caution block, and if this same current were used for operating the track relay the removal of energy from one block would effect removal of energy from the next block in the rear, this now being a caution block, and this block in turn would cut off the energy of the next block in the rear, and so on ad infinitum; and for this reason it is impracticable to use the same current for train control purposes and for track relay control purposes in a system of this kind. One expedient heretofore proposed is the use of direct current in the track circuit for track relay control purposes and in superimposing alternating current thereon under clear traffic conditions only, so that there is only direct current flowing in the track circuit under caution traffic conditions but alternating current also is flowing therein under clear traffic conditions. Several other important problems in two position continuous inductive train control systems are: the necessity of means requiring the engineer to manifest his vigilance in entering a caution block and in passing successive stop signals, and the need of amplifying means which will not produce a false clear indication due to an internal electrical disturbance in the car-carried system, for instance, such as, voltage fluctuations due to commutator construction known as "commutator ripples", and the like.

In view of the above and other important considerations, it is proposed in accordance with the present invention to use alternating current of one frequency for track relay control purposes and use alternating current of another frequency for train control purposes, and to apply the alternating current for

track relay control purposes at the entrance ends of the blocks for the normal direction of traffic, and to apply the alternating current for train control purposes at the exit ends of the blocks; to arrange the amplifying apparatus in a manner so that voltage fluctuations due to commutator ripples will not be applied to the grid of the first of the two successive audions, so that such fluctuations will not be amplified by the first audion; and to provide suitable cab signaling means which will inform the engineer as to traffic conditions ahead and as to when he must acknowledge or manifest his vigilance.

Other objects, purposes and characteristic features of the invention will appear from the description of the invention, and will in part be obvious from the drawing.

In describing the invention in detail reference will be made to the single figure of drawing in which both the car-carried and trackway apparatus of one particular train control system embodying the present invention has been shown.

Referring to the drawings it appears expedient to divide the system as shown into three distinctive parts; namely, the trackway apparatus, the influence transmitting and amplifying mechanism, and the train control and cab signal mechanism; therefore, these parts will be considered separately.

Trackway apparatus.

In the arrangement shown the track rails 1, have been divided by insulating joints 2, into blocks in the usual way, of which the block I and the adjacent ends of two other blocks H and J have been shown; and since these various blocks are the same, like parts of each block are designated by like reference characters having distinctive exponents. At the entrance end of each block, the normal direction of traffic being as indicated by the arrow, is provided a wayside signal Z, which may be a light signal or a semaphore signal and which for convenience has been illustrated as a semaphore signal of the three position type.

Across the rails at the entrance end of the block is impressed an alternating current derived from a transformer 5 which is connected to a transmission line 60 carrying a current having a suitable commercial frequency, such as 60 cycles, for instance, and across the exit end of each block is connected

a track relay T which has its local winding 6 connected to the same source of current, proper phase displacement between the currents in the windings of this track relay being obtained in any suitable manner. Since the track relay is at the exit end of the block it is necessary to repeat the indication to the entrance end of the block, and for this purpose the polar-neutral line relay LR is employed. This line relay LR is controlled by a pole changer switch PC controlled by the next signal in advance, that is Z', in a manner to apply positive energy to the relay LR when the signal next in advance is in either the clear or caution position and to apply negative energy to the relay LR if said signal in advance is at danger, energy being entirely cut off from the line relay LR by the contact 7 if the track relay of the block in question is in its retracted or de-energized condition. The signal Z is controlled by the line relay LR in the usual manner, which needs no further description; the common return wire 8 of the signal Z, however, contrary to the usual practice includes a front contact 9 of a check relay CK more particularly described hereinafter. The description thus far has been directed only to wayside signal apparatus, and we will presently consider the trackway train control apparatus.

In order to allow a train equipped with two position continuous inductive train control apparatus to proceed, it is necessary to impress a potential of train control current of a suitable frequency distinctive from the track circuit frequency across the exit end of a block, so that this current may flow down one rail through the wheels and axles of the train and back through the other rail, and for this purpose the transformer 12 is employed. The circuit for applying this train control current across the exit end of the block includes, a back contact 13 of the track relay T, a front contact 14 of the line relay LR of the block in advance, and a contact 15 on the signal blade of the signal Z' closed when the signal is in either the clear or the caution position, from which it will appear that the alternating train control current is not applied across the exit end of the block unless traffic conditions are clear and then not until a train has entered such block and has dropped the track relay thereof. This latter feature causes the secondary winding of the transformer 12 to partially shunt the track relay only when the block in question is already occupied, and does not leave this partial shunt on the track relay under normal clear traffic conditions. In this connection it is desired to point out that under ordinary conditions the track relay T will pick up even though the secondary winding of transformer 12 does partially shunt this relay, when this relay is dropped, of course assuming the block to be unoccupied at this time,

That is, a train passing through block I drops relay T, and causes the secondary of transformer 12 to shunt the relay T, but upon block I becoming unoccupied again, this shunt around relay T does not prevent the track circuit current from picking relay T up again. This transformer 12 has its primary winding connected to a transmission line 150 which supplies alternating train control current of a suitable frequency distinctive from the track circuit current frequency, and which for convenience may be assumed to be 150 cycles. For a short distance near the exit end of each block is provided means for causing current to flow in the same direction in both of the rails in multiple; this in order to compel the engineer to manifest his vigilance as he passes by this short section under adverse traffic conditions ahead. In the particular arrangement shown, balancing resistances 18 and 19 are connected between the track rails at two spaced points near the exit end of the block, and to the middle point of each of these resistances is connected one terminal of the secondary winding of a transformer 20. In order to assure that this current flowing in the same direction in both of the rails, that is, simplex current, is present the check relay CK is connected in series with this circuit, and the front contact 9 of this check relay is included in the common return wire 8¹ of the signal next in advance. The purpose of this simplex current will be more particularly pointed out hereinafter. At this point it may be well to note that the secondary winding of the transformer 5 has an impedance 17 connected in series therewith for limiting the current flow therein. The secondary winding of the transformer 12 preferably has sufficient internal ohmic resistance to limit the current flow therein, or has a suitable filter connected in series therewith which limits the flow of current of track circuit frequency only.

Car-carried apparatus influence transmitting and amplifying mechanism.

The car-carried apparatus includes a main relay MR having windings 30 and 31 which are at times energized by suitable amplifying means, to the plate circuits of which these windings are connected. More specifically these windings 30 and 31 are connected across the inductive reactances 32 and 33 included in the plate circuits of the audions A¹ and A² respectively, the arrangement being such that if these audions A¹ and A² have their grids excited by opposite relative polarities of an alternating current the relay MR will be energized to its normal condition, in which its contacts 36 and 37 assume the positions in which they are shown. This functioning of the relay MR in response to two alternating current potentials of opposite relative polarities is preferably accomplished by making

the circuit for one of these windings highly reactive and the circuit for the other winding high resistive or condensive; this may be accomplished by selecting the windings 30 and 31 and the capacities of the blocking condensers 38 and 39 properly, or it may be accomplished by any other and well known means. The filaments of the audions a^1 and A^1 are connected in series and have connected therebetween a filament resistance R^1 , these three elements in series being connected across the terminals of a filament generator FG, the plate circuit current for the various audions a^1 A^1 a^2 A^2 being derived from a high voltage plate generator PG. The filaments of the audions a^2 and A^2 are connected to the generator FG in the same way as are the filaments of a^1 , A^1 . The return ends of the grid circuits of the audions A^1 , A^2 are connected to the negative terminal of the filament generator FG and include the windings of the auto-transformers AT^1 and AT^2 respectively. From this arrangement it will be seen that the grids of the audions A^1 , A^2 are considerably negatively biased due to the drop of potential across the resistances R^1 and R^2 respectively, as well as due to the potential drop across the filaments of audions a^1 and a^2 . A potential is applied to the primary portion of the transformers AT^1 and AT^2 by the alternating current potential drop across the inductive reactances 40 and 41 respectively in the plate circuits of the audions a^1 and a^2 , and the alternating current flowing due to this potential flows through the condensers 42 and 43 respectively.

Mounted on the railway vehicle, which has been illustrated by the wheels and axles 46, and in front of the first wheels and axle thereof are receivers 47 and 48 having windings 49 and 50 thereon which are tuned or resonated to the frequency of the train control current by condensers 51 and 52 respectively. One end of each of the windings 49 and 50 is connected to the common return wire 54 from whence they lead through the grid bias battery CB, commonly known as a "C" battery, to the negative terminal of the filament generator FG, the other ends of the coils 49 and 50 being led through the reversing switch RS to the grids of the audions a^1 and a^2 respectively. From this construction it appears that the "C battery" CB applies a negative bias to the grids of the audions a^1 and a^2 respectively which audions comprise the first stage of the amplifying mechanism, the second stage including the audions A^1 and A^2 .

If the railway vehicle 46 enters a clear block, train control current will flow toward the train in one rail through the wheels and axle of the train and away from the train in the other rail, and this train control current impresses relatively opposite alternating potentials on the grids of the audions a^1 and a^2 respectively, which audions in turn apply am-

plified alternating current potentials to the grids of the second stage audions A^1 and A^2 respectively, and which in turn produce a flow of alternating current in the relay MR to cause it to assume its normal position. When the train enters the short section between balancing resistances 18 and 19 the effect of the current produced by transformer 12 predominates over the effect produced by the current derived from the transformer 20 so that no change in the condition of the main relay MR takes place when passing from left to right into the section 18-19 under clear traffic conditions of the block. If a train enters a caution block from which the supply of train control current connected across the exit end of the block has been removed, as for instance by the dropping of contact 14¹, the relay MR assumes its de-energized position, and when the train passes beyond the balancing resistance 18, and encounters the simplex current flowing through the rails in multiple, and supplied by transformer 20, the induced voltage in coils 49 and 50 will be in phase, instead of in opposition, whereby the relay MR is energized to the reverse or left hand dotted position. As described above, with loop current in the rails, the main relay MR is so connected up as to be energized to normal position. In changing from loop to simplex current in the rails, as between balancing resistances 18 and 19, the net effect is to have left one of the loop currents unchanged, and to have changed the other 180°, i. e., to have reversed the other. Thus, if with loop current, the relay MR is acted on by two currents displaced about 90° in phase, then with simplex current, the relay is acted on by two currents likewise displaced in phase about 90°; but the displacement is in the angular direction reverse to the normal displacement. For a further and more detailed description of an amplifier of this general type reference may be had to the prior application of William D. Hailes #752,338 filed Nov. 26, 1925. A more detailed functioning of the system will be described under the head of "operation" hereinafter.

Train control and cab signaling mechanism.

The particular train control mechanism illustrated in the present embodiment of the invention is one of the permissive type, in which the unrestricted progress of the train is only interfered with in the event the engineer is not attending to his duties and does not manifest his vigilance when he should; and in order for the train to proceed in territory where there is no train control current flowing in the usual trackway circuit there is provided a supplemental relay, which may be energized by the engineer when he manifests his vigilance by performing a manual act upon his entrance into territory in which adverse traffic conditions exist. In the ar-

angement shown this relay which is conveniently called an acknowledging relay has been designated AR. By the arrangement shown it is possible for the engineer to pick up this acknowledging relay AR if he depresses the acknowledging push button *Ack* before the brake control relay BR is de-energized. The normal energizing circuit for the brake control relay BR may be traced as follows:—
 10 beginning at the terminal B of a suitable source of energy, contact 37 of the main relay MR in its normal position, wires 61, 62 and 63, winding of the brake control relay BR, to common return wire C connected to
 15 the other terminal of said source of energy. The circuit just traced is also closed when the main relay MR is in the reverse position in which event the wire 64 is included in the circuit. With the brake control relay BR
 20 energized the electro-pneumatic brake applying device E. P. V. is energized through the following circuit:—beginning at the terminal B, wire 67, normally closed contact 68 of the acknowledging button *Ack*, wire 69,
 25 normally closed contact 70 of the reset push button RS, wire 71, front contact 72 of the brake control relay BR, wire 73, winding of the device E. P. V., to common return wire C connected to the other side of said source.
 30 Also, the lamp G is energized under normal clear traffic conditions through a circuit including the contact 36 of the main relay MR, which circuit may readily be traced in the drawing.

35

Operation.

For reasons heretofore given, with a train passing along the trackway under clear traffic conditions the main relay MR will remain in its normal energized condition when passing through the sections 18—19 because the simplex current flowing between the balancing resistances 18 and 19 near the exit end of each block is insufficient to interfere with the proper energization of the main relay MR by the train control track circuit current supplied by transformer 12, that is, the train control current is the predominating current of these two currents.

Let us assume that the engineer is not vigilant, and that the block J in the particular arrangement shown is occupied by another train, which of course will cause the line relay LR¹ to assume the de-energized condition.

As soon as the train 46 in block H enters the block I, the track relay T assumes its de-energized condition and closes its contact 13, but the dropping of this contact will not cause the application of train control current to the block I because the contact 14¹ is now open. Since, as has been assumed, the train 46 has entered the block I without the engineer manifesting his vigilance an automatic brake application will occur, because the contacts of the main relay MR now as-

sume their retracted position thus causing the brake control relay BR to assume its de-energized condition, and the act of acknowledging at this time is of no avail because the pickup circuit for the relay AR (traced below) is open at front contact 92 of relay BR.

With the brake control relay in its retracted condition, the brake applying device E. P. V. is thus de-energized and brings the train to a stop. As soon as the train has been brought to a stop the engineer if he wishes to again proceed may alight to the ground and operate the reset push button RS, which is only accessible from the ground. If the push button RS is depressed the following circuit for picking up the acknowledging relay AR is closed:—beginning at the terminal B, contact 37 of the main relay MR when in its de-energized pendant position, wire 76, normally open contact 77 of the reset button RS, wires 78 and 79, upper winding 80 of the acknowledging relay AR, to common return wire C connected to the other side of the said source of energy. This causes the acknowledging relay AR to assume its energized condition thus causing the following stick circuit to be closed, bearing in mind that the main relay is still de-energized:—beginning at the terminal B contact 37 of the main relay MR, wire 81, front contact 82 of the acknowledging relay AR, the lower winding 84 of the acknowledging relay AR, wire 83 to common return wire C. With this stick circuit closed the acknowledging relay AR is stuck up, and the closure of its front contact 85 will close a

circuit for energizing the brake control relay BR, which may be traced as follows:—beginning at the terminal B, front contact 85 of the acknowledging relay AR, wires 86 and 63, winding of the brake control relay BR, to common return wire C. The engineer may now return his reset push button to normal thereby closing the contact 70, and since the contact 72 is now closed the device E. P. V. will again assume its energized inactive condition. This expedient of including the contact 70 of the reset push button RS in the circuit of the device E. P. V. is resorted to in order to avoid the reset push button RS being tied or otherwise fastened in its active position permanently.

Let us now assume that the train in question passes from the block H into the block I while the block J is occupied by another train, and that the engineer is attending to his duties and realizes that he is about to pass a signal at caution and manifests his vigilance by depressing the acknowledging push button *Ack*. In depressing this push button *Ack* a pick up circuit for the acknowledging relay AR is completed which may be traced as follows: beginning at the terminal B, contact 90 of the acknowledging push button *Ack*, wire 91, front contact 92 of the brake control relay BR, wires 93 and 79, wind-

ing 80 of the acknowledging relay AR to common return wire C. It should be noted that the engineer is given a time interval within which to acknowledge, after de-energization 5 of BR, equal to the release time of such relay BR. The engineer will maintain the acknowledging push button Ack in its depressed position until the train has entered the caution block I and the main relay MR 10 has assumed its de-energized position; this is permissible even though the contact 90 is closed for an appreciable time, because the contact 68 will not open the circuit for the device E. P. V. until a certain interval of time 15 has elapsed, this by reason of the retarded action effected by a suitable time element device which prevents the contact 68 from immediately opening, which time element device in the particular arrangement shown has 20 been conventionally illustrated by the dash pot 95. It is desired to point out that the acknowledging means effective for a predetermined time only, if actuated, is merely an illustration of suitable means for accomplishing 25 the desired result, and that any other suitable means may be used, if desired. As soon as the main relay MR assumes its de-energized condition the stick circuit for the acknowledging relay AR heretofore traced 30 is again closed, so that the brake control relay and in turn the device E. P. V. is maintained energized, the device E. P. V. being held inactive in spite of the fact that there is no train control current flowing in opposite directions in the two rails ahead of the train. 35

The train is thus permitted to proceed through the caution block under the control of the engineer even though the relay MR is de-energized, but he is doing so at his own 40 risk and is informed of this fact by the illumination of the red danger signal R. Upon entrance of the train into the acknowledging section 18-19 the relay MR is energized to the reverse position, as explained 45 above, under which condition the relay BR is again energized through its normal circuit including contact 37 in its reverse or left hand position, the moving of finger 37 of relay MR to an energized position breaking the stick circuit 50 for relay AR. At this time the purple acknowledging signal lamp P is illuminated instead of the clear lamp G, and the engineer is thereby informed that he is just about to enter a danger block and that he is required to manifest his observance and recognition of 55 these facts. With the acknowledging relay AR de-energized and the brake control relay BR maintained up by a circuit including the reverse contact of the main relay MR the 60 train may proceed over the acknowledging section 18-19, and if the engineer does not manifest his vigilance until after the drop away period of BR after entering the occupied block J a brake application will, of

course, occur. If the engineer, however, depresses the acknowledging push button Ack before the relay BR drops due to the main relay assuming the de-energized position the acknowledging relay is stuck up, as heretofore described, and the train may proceed 65 under the control of the engineer until it enters another caution or danger block, or zone. 70

It is observed that the train is permitted to proceed in clear territory in response to 75 current flowing in the track rails; also, it is well to know that such current cannot very well be supplied at dead sections, such as, railway crossings, frogs, switches, or at junctions between blocks where the insulating 80 joints are staggered, and it is primarily for this reason that the brake control relay BR is constructed to be slow releasing. The time required for the relay BR to assume its retracted position after its energizing circuit 85 is broken is preferably such that a train moving at a speed of say 15 miles per hour will not allow this relay to drop during the time the train passes over the longest dead section 90 on the railroad. The engineer is thus not required to acknowledge dead sections. If traffic conditions clear up with the train at an intermediate point in the block, the cab signal will change from red to green, and the brake control relay will be directly energized by the main relay; by this information 95 the engineer is aware of the fact that he may accelerate his train.

It should be noted that, in general, if stray currents are flowing in multiple, along the 100 trackway, of a frequency to which the car-carried apparatus will respond, this flow of current may cause the relay MR to assume its reversed dotted position, in the same manner as does the simplex current from the 105 transformer 20. If, therefore, stray currents are encountered in a caution or danger block, where, the relay AR is stuck up due to acknowledgment at the entrance to said block, the engineer will be informed of such stray 110 currents by illumination of the purple lamp P, while the stick circuit for AR is broken at finger 37 of MR, and, if he is not to incur an automatic brake application after the stray current ceases to flow he must again 115 acknowledge and thus again pick up the relay AR or a brake application will occur when such stray current ceases to flow and relay MR again assumes its de-energized position. 120

Also, due to the manner in which they are connected in the system, if either of the generators FG and PG should develop fluctuations of potential in the car-carried system, the effect of such fluctuations in the currents applied to the main relay MR will be such as to cause this relay to assume its reversed position, assuming of course that they are of 125

sufficient amplitude to operate the relay, and thus will not energize MR to normal to thus set up a false clear indication on the train.

In this connection, it should be noted, that 5 the various switches and amplifiers are so connected, that any voltage fluctuation developed in either of the generators, will have the same effect on all the various filaments and grids of the amplifiers, and the relay MR, 10 and its windings are so connected that the torque produced in relay MR by such fluctuation, will be a torque to reverse position. It is, of course, understood, that coils 48 and 49 are so connected to the grids of amplifiers a^1 15 and a^2 that simplex current will have the same effect on relay MR as the currents produced by generator ripples, while loop currents will have the opposite effect.

Although the alternating current applied 20 for wayside signaling and track relay control purposes is applied at the entrance end of the block and therefore cannot readily reach the influence receiving elements 47 and 48, suitable current filtering apparatus may be used 25 in the car-carried circuits, so that the car-carried apparatus will not respond to currents other than the train control currents, which are of the proper frequency. It should be noted that there are provided at the rear 30 end of the motor car, or the rear end of the tender as the case may be, elements 47¹ and 48¹ having windings 49¹ and 50¹; these windings are substituted in the amplifier circuits for the windings 49 and 50 respectively, when 35 the engine and tender unit is operated tender first, instead of pilot first. If the engine and tender unit is operated tender first the reversing switch RS is moved to the dotted position, either manually or by suitable means responsive to the direction of movement of the train. 40

Having thus shown and described one specific embodiment of the present invention, and having given a rather complete description of the system shown; it is desired to be understood that the particular arrangement shown and described has been selected for the purpose of disclosing the nature of the invention rather than its scope, or the particular arrangement preferably employed in practice; and that various changes, modifications and additions may be made to adapt the invention to the particular type of railway in connection with which it is to be used, or to adapt it to the particular form of restriction in 55 the progress of the vehicle which is to be imposed, all without departing from the scope of the invention or the ideas and means underlying the same.

What I claim as new is:—

60 1. Trackway apparatus for automatic train control systems of the continuous inductive type comprising, a trackway divided into blocks by insulating joints, a source of alternating current of one frequency connected across the track rails at the entrance end of

the block, a track relay responsive to said frequency connected across the track rails at the exit end of the block, means for producing a flow of alternating train control current of a different frequency in the same direction in 70 both rails near the exit end of the block, and means for applying alternating train control current of said different frequency across the rails at the exit end of the block if the block next in advance be unoccupied, for controlling a train equipped with train control apparatus of the continuous inductive type, the relative strengths of said train control currents of said different frequency being such that the one applied across the rails at the 75 exit end predominates, and car-carried train control apparatus cooperating with the trackway apparatus.

2. Trackway apparatus for automatic train control systems of the continuous inductive type comprising, a trackway divided into blocks by insulating joints, a source of alternating signaling current of one frequency connected across the track rails at the entrance end of the block, a track relay responsive to said frequency connected across the track rails at the exit end of the block, means for producing a flow of alternating train control current of a frequency different from 85 said one frequency in the same direction in 90 both rails near the exit end of the block, and means for applying alternating train control current of said distinctive frequency across the rails at the exit end of the block if the next block in advance is unoccupied, whereby 95 a train moving in the normal direction of traffic may detect the two said distinctive train control currents but not signaling current and train control apparatus associated with the trackway apparatus.

3. Trackway apparatus for automatic train control systems of the continuous inductive type comprising, a trackway divided into blocks by insulating joints, a source of alternating current of one frequency connected across the track rails at the entrance end of the block, a two element track relay responsive only to said frequency having one of its windings connected across the track rails at the exit end of the block, means for continuously causing a flow of alternating current of a distinctive frequency in the same direction in both rails near the exit end of the block, and means for applying alternating current of the same distinctive frequency 110 across the rails at the exit end of the block when said track relay is de-energized and the next block in advance is unoccupied; and train control apparatus for cooperating with the trackway apparatus.

4. In an automatic train control system of the continuous inductive type, the combination with trackway apparatus including means for constantly applying alternating current flowing in the same direction in the 120 125 130

- two track rails of a short section near the end of a block for enforcing vigilance of the engineer when passing a wayside signal indicating adverse traffic conditions, means for 5 applying alternating current of the same frequency as said first mentioned alternating current across the rails at the exit end of the block so as to cause alternating current to flow down one rail and back through 10 the other when the next block in advance is unoccupied, the relative strength of said currents being such that the current applied across the rails at the exit end of the block predominates over the current 15 flowing in the same direction in both rails; and of train carried apparatus including a three position relay which will assume its normal position in response to current flowing down one rail and back through the 20 other and will assume the reversed position in response to current flowing in the same direction in both rails, and means requiring the engineer to make an acknowledging act each time the relay assumes the reversed 25 position.
5. In an automatic train control system of the continuous inductive type, the combination with trackway apparatus including means for constantly applying alternating current flowing in the same direction in the two track rails of a short section near the end of a block for enforcing vigilance of the engineer when passing a wayside signal indicating adverse traffic conditions, means for 30 applying alternating current of the same frequency as said first mentioned alternating current across the rails at the exit end of the block so as to cause alternating current to flow down one rail and back through the 35 other when the next block in advance is unoccupied, the relative strength of said currents being such that the current applied across the rails at the exit end of the block predominates over the current flowing in the 40 same direction in both rails; and of train carried apparatus including a three position relay which will assume its normal position in response to current flowing down one rail and back through the other and will assume the reversed position in response to current 45 flowing in the same direction in both rails, means requiring the engineer to acknowledge his vigilance each time the relay assumes the reversed position, and means for causing the 50 signal at the entrance end of the next block in advance to indicate stop in spite of favorable traffic conditions ahead if the means for applying alternating current to said short section fails.
- 55 6. Amplifying apparatus for amplifying currents flowing in the track rails in a train control system comprising, two audions each having a filament, a grid and a plate; a circuit for energizing the two filaments of said audions including the filaments and a grid bias resistance in series, said resistance being contained between said two filaments; and a source of direct current energy having its negative terminal connected to the free end of the filament of the first audion and the 60 positive terminal connecting to the free end of the filament of the second audion; the grid circuit of the first audion having a grid bias battery connected in series therewith, and the grid circuit for the second audion having its 65 grid return wire connected to the negative terminal of said source of energy; whereby a negative bias is applied to both of the grids of said audions and whereby fluctuations due to commutator ripples are not amplified by 70 the first audion.
7. Amplifying apparatus for automatic train control systems of the continuous inductive type comprising in combination, a first and a second audion each having a filament, a plate, and a grid; a filament circuit including the two filaments and a filament source of current in series so that the filament of the second audion is connected to the positive terminal of said source and filament 75 of the first audion is connected to the negative terminal of said source, a grid bias battery in the grid circuit of the first audion, the return wire of the grid circuit of the second audion being connected to the negative terminal of said source; whereby the grids of 80 both audions are negatively biased, and whereby voltage fluctuations of said source are not amplified by said first audion.
8. Car-carried apparatus for automatic 85 train control systems of the continuous inductive type comprising in combination; a three position relay which assumes its normal position under favorable traffic conditions ahead and assumes its reversed position when it approaches a signal indicating adverse traffic conditions; a stick relay; a slow acting relay maintained energized if said three position relay assumes either the normal or the reverse position or if said stick relay assumes 90 the energized position; said stick relay having a pick up circuit including a front contact of said slow acting relay and an acknowledging push button contact in series; a stick circuit for said stick relay including a front contact thereof and a contact closed when said three position relay is de-energized; and a brake control device governed by said 95 slow acting relay.
9. Car-carried apparatus for automatic 100 train control systems of the continuous inductive type comprising in combination; a three position relay which assumes its normal position under favorable traffic conditions ahead and assumes its reversed position when it approaches a signal indicating adverse traffic conditions; a stick relay; a slow acting relay maintained energized if said three position relay assumes either the normal or the reverse position or if said stick relay assumes 105 the energized position; said stick relay having a pick up circuit including a front contact of said slow acting relay and an acknowledging push button contact in series; a stick circuit for said stick relay including a front contact thereof and a contact closed when said three position relay is de-energized; and a brake control device governed by said 110 slow acting relay.
10. Car-carried apparatus for automatic 115 train control systems of the continuous inductive type comprising in combination, a three position relay which assumes its normal position under favorable traffic conditions ahead, assumes its de-energized under dangerous 120 traffic conditions, and which for a time assumes its reversed position when it approaches a signal indicating adverse traffic conditions; a stick relay; a slow acting brake control device maintained energized if said 125 130

- three position relay assumes either the normal or the reverse position and which is energized if said stick relay assumes the energized position said stick relay having a pick up circuit including a front contact of said slow acting brake control device and an acknowledging push button contact in series; a stick circuit for said stick relay including a front contact thereof and a contact closed when said three position relay is de-energized; whereby the engineer is required to manifest his vigilance by picking up said stick relay upon his entrance into territory where adverse traffic conditions exist.
15. 10. In an automatic train control system of the continuous inductive type, the combination with trackway apparatus including means for constantly applying alternating current flowing in the same direction in the two track rails of a short section near the end of a block for enforcing vigilance of the engineer when passing a wayside signal indicating adverse traffic conditions, means for applying alternating current of the same frequency as said first mentioned alternating current across the rails at the exit end of the block so as to cause alternating current to flow down one rail and back through the other when the next block in advance is unoccupied, the relative strength of said currents being such that the current applied across the rails at the exit end of the block predominates over the current flowing in the same direction in both rails; and of train carried apparatus including a three position relay which will assume its normal position in response to current flowing down one rail and back through the other and will assume its reverse position in response to current flowing in the same direction in both rails, means requiring the engineer to manifest his vigilance each time the relay assumes its reverse position, and means for causing the next signal in the rear to indicate non-clear traffic conditions if the means for applying alternating current to said short section fails.

In testimony whereof I affix my signature.
WADE H. REICHARD.
